UNITED STATES PATENT OFFICE

2,297,391

GRINDING MILL

Friedrich Conradi, Magdeburg-Hopfgarten, Germany; vested in the Alien Property Custodian

Application March 26, 1940, Serial No. 325,991
In Germany March 4, 1939

1 Claim. (Cl. 83—93)

My invention relates to grinding mills, wherein the material to be ground is agitated in the presence of grinding elements; and more especially to improvements in gyrating grinding mills of the continuously acting type known for instance from United States Patent 2,117,965 to Kieskalt et al., which are bodily gyrated in small cycles of movement, and through which the material is gravitationally advanced.

The primary object of this invention is to provide an improved grinding mill of the continuously acting gyrating type set forth and of high efficiency, which is composed of a relatively small number of parts of simple structural design, and wherein various materials of different hardness, including for instance cement clinker, graphite, crushed ore, asbestos, burnt lime, etc. can be rapidly comminuted into powder of great fineness under conditions of economy namely as regards output, power consumption and expenses for repair and maintenance of the grinding mill.

Other objects aimed at by this invention and advantages obtained will become apparent to practitioners in this field as the description proceeds.

The nature and scope of the invention are briefly outlined in the appended claim and will be more fully understood from the following specification taken together with the accompanying drawing, in which

Fig. 1 is a section axially taken through a vertically disposed gyrating grinding mill, redesigned according to this invention, and

Figs. 2, 3 and 4 are sections axially taken through vertically disposed gyrating grinding mills of modified design.

In its original and simplest form the grinding mill, designed with the objects in view outlined above, and shown in Fig. 1 comprises:

(1) A drum shaped, vertically disposed grinding chamber 20 (Fig. 1) having a cylindrical grinding and impulse giving working face 21—hereinafter briefly called "impeller" face—and a bottom wall 22 formed with discharge holes 1,

(2) An apertured lid 32 and a hopper 33 yieldingly connected therewith by a flexible hose 34 for feeding the material to be ground into the mill,

(3) Chains 13, 13' or like suspending means for yieldingly supporting the mill and allowing of the latter being bodily gyrated transversely to its axis,

(4) A circular grinding element 40 in the form of a disc or ring, having a central intake and a slightly smaller diameter than the cylindrical im-

peller face of the grinding chamber 20, and being hereinafter briefly called "grinding ring"; said ring 40 gravitationally rests on and receives, gyroscopic impulses from the bottom 22 of the mill; by centrifugal forces thus produced in the grinding ring, the latter is positively kept in edgewise frictional engagement with the impeller face 21 and with the result that the ring by rolling off the latter revolvably moves in circular paths over the bottom-plate 22, namely revolving in a direction of rotation, opposed to that of the gyrating motion of the mill; and

(5) Means are provided for bodily gyrating the mill transversely to its axis in closed cycles of movement, which comprise a rotary shaft 50, axially journaled at the lid and bottom of the mill and being enclosed by a tubular member 51, unbalance weights 52, 52' attached to said shaft, and an electric motor 53 for rotating it.

In the embodiment of the invention shown by way of an example in Fig. 1 a plurality of spaced partition walls 23 to 31 are provided having discharge holes 12 to 110, distributed over their whole area; said partition walls subdivide the mill into a plurality of compartments, in each of which there is a grinding ring of specific design formed at its lower face with a bevelled circumferential edge 41 for promoting the passage of the ground material underneath the ring.

According to this invention the spaces between the successive partition walls 22 to 31 are progressively smaller towards the lower end of the mill; likewise the discharge holes 1 to 110 in the successive partition walls are progressively smaller towards the lower end of the mill namely in proportion to the gradually smaller size of the ground product.

The material under treatment gravitationally passes down through the successive compartments, is ground therein between the interengaging surfaces of the grinding rings and the grinding chamber and passes out of the mill through a funnel 14.

A great many changes and structural modifications may be conveniently made in the design, assemblage and cooperation of the various component parts of gyrating grinding mills as shown in Fig. 1 in order to obtain the best results on grinding various raw materials differing in their hardness and other physical properties, without departing from the spirit and the salient ideas of this invention.

In the structurally modified grinding mill shown in Fig. 2 there are means provided capable of adjustment from without the mill for keep-

ing the grinding ring r_3 resiliently pressed against the opposed partition wall p_3 of the grinding chamber; the said pressing means comprise a plurality of spaced double-armed levers 16 circumferentially distributed and engaging the grinding ring by means of a ball shaped pressing element 17 rotatably attached to lever 16 ; the said levers, of which one only is shown in Fig. 2, are loaded by springs 18 , the tension of which can be adjusted by means of a screw and nut gear $18'$ supported by a bracket 19 .

Underneath the partition walls p_2 , p_3 which are provided with spaced discharge holes d_2 , d_3 around their periphery, there are funnel shaped chutes t_2 , t_3 provided for establishing a zig-zag course for the material under treatment; the material entering at the center of the grinding ring r_3 , passes radially underneath the latter towards its periphery, and after having dropped through the discharge holes d_3 is collected in the chute t_3 and gravitationally redirected to the center of the next following grinding compartment.

With the structurally modified grinding mills shown in Figs. 3 and 4 a plurality of grinding rings are arranged in each grinding compartment:

The grinding rings r_6 , r_7 , r_8 , r_9 (Fig. 3) are superimposed on each other and formed at their intake holes with bevelled edges g_6 , g_7 adapted to promote the entrance of the material underneath the rings; the rings r_6 , r_7 , r_8 , r_9 have alternately different diameters and are thus caused to revolve at different speeds relatively to each other whereby the grinding action is enhanced.

For the same purpose the superimposed rings r_{10} , r_{11} , r_{12} may be in series graduated as to their diameters namely may have progressively larger diameters from top to bottom of the grinding chamber, as seen in Fig. 4. In other words, referring to both Figures 3 and 4, it will be apparent that the adjacent, that is, alternate rings have different diameters.

Heavier grinding rings r_{13} , r_{14} , r_{15} graduated as to their diameters and nested within each other, as seen in Fig. 3, may be used to advan-

tage in the upper grinding compartment or compartments of the mill, wherein the raw material is firstly subjected to the grinding action while the mill is gyrated. In the course of that movement, the grinding rings r_{13} , r_{14} , r_{15} because of their different diameters and their edgewise engagement with each other and the impeller face of chamber h_2 respectively, revolvingly move at different speeds in circular paths over the bottom plate of the mill, thereby grinding the material pinched between their upright and lower faces and the bottom of the mill.

The housings of the mills shown in Figs. 3 and 4 may be composed to advantage of a plurality of cylindrical shells h_2 , h_3 , h_4 , h_5 , h_6 provided with and interengaging each other by offset sleeves n_3 , n_4 , n_5 ; in this way the disassembly of the mill housing is facilitated for inspection and repair, for instance when worn grinding rings must be removed and replaced by new or reground ones.

Instead of suspending the grinding mill by means of chains 13 , $13'$ (Fig. 1) the mill may be yieldingly supported by a plurality of spaced springs 45 , $45'$ and brackets 46 , $46'$ circumferentially attached to the mill housing, as seen in Fig. 4.

I claim:

Mill for continuously grinding material in bulk comprising a drum shaped, vertically disposed grinding chamber, having a cylindrical impeller face and a bottom formed with discharge holes therethrough, means for feeding the material into said chamber, a plurality of grinding rings superposed upon each other, resting on the bottom of said chamber and being of smaller diameter than that of the impeller face, and of which alternate rings differ in their diameter from their mates, and means for bodily gyrating said chamber in closed cycles of movement transversely to its axis, so as to revolve said grinding rings relatively to the grinding chamber and in a direction of rotation opposed to that of the gyrating motion of the latter.

FRIEDRICH CONRADI.
